UNITED STATES PATENT OFFICE.

ALBERT J. KAUFMANN, OF WELLSBORO, PENNSYLVANIA, ASSIGNOR TO PET MILK COMPANY, OF ST. LOUIS, MISSOURI, A CORPORATION OF DELAWARE.

CAN-BODY ASSORTER AND PILER.

Application filed February 10, 1923. Serial No. 618,188.

This invention relates to an improvement in assorting and piling devices for receiving articles such as can bodies after the bodies or blanks have been made by the slitting or cutting machine, the primary object of the invention being for the purpose of assorting and piling the body blanks after the body blanks have been discharged from the cutting rollers of the slitting machine.

Another object of the invention is in providing an improved device of this character with means whereby some of the can body blanks upon being received are engaged and turned in such a manner during their discharge from the cutting rollers of the slitting machine so that the body blanks will finally lodge and face in the same manner or direction.

A further object of the invention is in providing a device of this improved character with means for stacking the body blanks in piles so that they can be readily removed therefrom in their piled or stacked arrangements.

Other and further objects will appear in the specification and be specifically pointed out in the appended claims, reference being had to the accompanying drawings, exemplifying the invention, and in which:—

Figure 1 is a plan view of this improved can body assorting and piling device.

Figure 2 is a side elevation of Fig. 1 taken in the direction of the arrow 2, showing the cutting roller shafts of the slitting machine with which this improved device is co-operable in section.

Figure 3 is a front elevation of Fig. 1.

Figure 4 is an enlarged diagrammatic view of one of the body blank receiving sections, showing the discharge of the body blanks thereto.

Figure 5 is a vertical section showing a metallic blank formed into a can body and ready for the reception of the closing ends.

With reference to the accompanying drawings, 1 designates a portion of a metallic sheet slitting machine, said machine having a co-operable pair of cutting rollers 2

and 3, the rollers 2 being provided with a series of pairs of cutting edges 4, whereas the rollers 3 are provided with a series of pairs of cutting edges 5, each pair of cutting edges 4 being co-operable with a respective pair of cutting edges 5 of the roller 3. 50 55

Secured horizontally to the portion 1 of the slitting machine is a cross member 6, said member being for the support of a series of receiving chutes 7 which are arranged inclining downward from the slitting machine as shown more clearly in Fig. 2, and for supporting the lower arranged discharging ends of said chutes is a horizontally disposed cross member 8 which is supported by upwardly extending legs 9. 60 65

Each of the chutes 7 is comprised of a box like structure 10 having a bottom 11, a vertically extending side wall 12 and an outwardly inclining side wall 13 which is disposed opposite from the side wall 12 as 70 shown more clearly in Fig. 4.

Secured to each of the inclining walls 13 of each chute 7 is a deflecting member 14 having a curve portion 15, said deflecting member being relatively short in length and 75 disposed adjacent one end of the wall 13, and extending downwardly from the upper end of each wall 12 of each chute 7 is an inclined deflecting member 16, said deflecting member 16 being oppositely disposed from 80 the deflecting member 14 and being shorter in length than the wall 12.

As shown in Fig. 2, the chutes 7 are disposed on an incline in which the upper ends 17 of said chutes are adjacent the cutting 85 rollers 2 and 3 and located below and adjacent the lower end 18 of each chute is a receiving hopper 19, each hopper being removably supported between a respective pair of guides 20, said guides being held in 90 an inclined position by the supporting structure 21.

The cutting edges 4 and 5 of the respective rollers 2 and 3 are spaced apart and arranged so that a respective cutting edge 4 will co-operate with a respective cutting

edge 5 so that when a metallic sheet is passed between the rollers, the sheet will be cut in strips, each strip providing a can body blank, and in the operation of the spaced apart cutting edges 4 and 5 body blanks will be formed in the places marked A and B and the discharge of the blanks A¹ and B¹ from the places A and B will be in respective chutes 7 and in which the discharge

10 of all of the blanks of a sheet length will be made in pairs into the respective chutes.

Upon the discharge of the blanks in pairs into the respective chutes 7 the blank A¹ will engage the inclined surface of the deflecting member 14 and in the downward travel thereof on said surface the blank will travel around the curved portion 15 of said member 14 and assume the approximate position shown at A² in Fig. 4 and from which position the blank will tend to fall in the position shown at C in said figure and finally be deposited on the bottom 11 of its respective chutes 7 and inasmuch as said bottom 11 is inclined towards its respective hopper 19 the blank will finally be discharged from the bottom 11 of the chute 7 into the hopper 19.

From an inspection of Fig. 4 it will be seen that the cutting operation of the cutting edges 4 and 5 formed downwardly extending burrs 22 on each edge 23 of the blank A¹, whereas an upwardly extending burr 24 was formed on each edge 25 of the blank B¹, said edges 23 and 25 of the respective blanks forming the upper and lower ends of the can body to which the can top and bottom are subsequently secured and in this connection it is essential that the burrs extend inwardly as shown in Fig. 5 when the blank is subsequently formed into a can body by the can body forming machine. This invention is therefore designed for the purpose of receiving the can body blanks from the slitting machine and piling the blanks in a manner so that the burrs of the blanks will be turned in the same direction during the piling operation.

The blank B¹ upon being discharged from between the rollers 2 and 3 simultaneously with the discharge of the blank A¹ will engage the deflecting member 16 of a respective chute 7 and assume the position shown at B² and inasmuch as the deflecting member 16 is relatively short in length the blank B² will be discharged from the member 16 as it travels forwardly and downwardly and in falling from the member 16 will assume the position C as did the blank A¹ and engage the incline bottom 11 of its respective chutes 7 from where it will be discharged into its respective hopper 19.

During the operation of this improved device, as the respective hoppers 19 are filled with piled blanks, they are each removed

from the supporting structure 21 and carried to the can body forming machine.

What I claim is:

1. An assorting and piling device for receiving articles in pairs comprising a pathway for the discharge of each article, and overturning means arranged in the path of discharge of one of the articles of each pair of articles.

2. A piling device adapted to receive articles which are discharged in sidewise pairs thereto comprising a receiving chute, and means disposed in said chute to be engaged by one of the articles of each pair of articles for overturning one of the articles.

3. A piling device adapted to receive articles which are discharged in sidewise pairs thereto comprising a receiving chute, means disposed in said chute to be engaged by one of the articles of each pair of articles for overturning one of the articles, and other means provided in the chute whereby the articles are finally piled one upon another.

4. An assorting and piling device for articles which are discharged in sidewise pairs along separate pathways comprising an overturning element located in the pathway of one of the articles for overturning one of the articles and throwing it in the pathway of the other article.

5. An assorting and piling device for articles which are discharged in pairs along separate pathways comprising a receiving chute, means arranged in the pathway of one of said articles for overturning one of the articles of the pair of articles as the articles are being discharged into said chute, and other means provided in the chute whereby the articles are finally piled one upon another.

6. A receiving chute for receiving blanks after being formed and discharged in sidewise pairs comprising a deflecting member arranged within said chute on one side thereof and in the path of discharge of a blank of each pair of discharged blanks for engaging one of each pair of blanks as they are discharged through said chute, said deflecting member adapted to overturn each blank engaged thereby.

7. A receiving chute for receiving blanks after being formed and discharged in sidewise pairs comprising a deflecting member arranged within said chute on one side thereof and in the path of discharge of a blank of each pair of discharged blanks for engaging one of each pair of blanks as they are discharged through said chute, said deflecting member adapted to overturn each blank engaged thereby, and means provided for piling the blanks upon one another.

8. An assorting and piling device for articles which are received in pairs therein comprising a chute, a pair of deflecting members arranged in said chute each adapted to be

engaged by a respective article of each pair of articles as they are discharged in said chute, one of said deflecting members adapted to overturn each article engaged thereby.

5 9. A receiving chute through which articles are passed in sidewise disposed pairs, said chute having a deflecting member ar-

ranged therein wherein it will be engaged by only one of each pair of discharging articles, and means provided in said chute whereby one of the articles will fall directly on the other article of each pair of articles.

ALBERT J. KAUFMANN.
